REVOLVING FAN SPEED CONTROL

Ely Primeaux, Alexandria, La.

Application December 17, 1945, Serial No. 635,508

10 Claims. (Cl. 230—270)

1

This invention relates to a revolving fan speed control, and more particularly to a type of construction wherein two or more fans revolve or gyrate around a main support, and the assembly of a speed control whereby it is possible to regulate the speed of the fans rotating around said support.

An object of the invention is to provide a speed control means by which the speed of the fans driven by individual motors, such as electric motors, may be set to operate at predetermined speeds within certain limits so that when due to the same tending to run beyond set speeds, an automatic brake will be applied by centrifugal action, to check and maintain the speed uniform or below a predetermined or excessive limit.

Another object of the invention is to provide a novel drive mechanism for supporting the plurality of individual fans rotating around the support including said driving mechanism, and means governor operated, to automatically control and maintain the speed of the fans in revolving around the support, at a predetermined limit.

Other objects and advantages reside in the details of construction and operation as more fully hereinafter described and claimed, reference being had to the accompanying drawings forming part hereof, wherein like numerals refer to like parts throughout, and in which:

Figure 1 is a side elevation of a fan having a speed control constructed in accordance with the invention.

Figure 2 is a sectional elevation taken on the line 2—2 of Figure 1.

Figure 3 is a section taken on the line 3—3 of Figure 2.

Figure 4 is a section taken on the line 4—4 of Figure 2.

Figure 5 is a horizontal sectional view taken on the line 5—5 of Figure 2, and

Figure 6 is a vertical sectional view taken on the line 6—6 of Figure 2.

Referring to the drawings in detail, in which like reference characters designate corresponding parts throughout the several views, the fan is shown as comprising a main stationary hangar or support 10 suspended in a suitable manner as from a ceiling, such as by means of a plate 11 suitably secured to the ceiling and in which the upper end of the hangar or support may be secured as by threading or otherwise so as to be suspended or hung therefrom. At the lower portion of the hanger and support 10 is a revolving carriage or gear box 12, the same enclosing the

2

driving mechanism and preferably being in the form of a frame of square or rectangular form open at the opposite sides. The top is provided with a depending bearing sleeve 13 which revolves on the circular tubular hanger and support 10 and rotates at its lower end on a thrust bearing 14 resting on the sleeve or hub 15 of a large stationary spur gear 16 keyed or fixed to the hanger 10 as at 17 and retained by a nut 18 threaded on the lower end of the hanger 10. In this manner, the revolving carriage, frame or box 12 is supported for free rotation with a minimum of friction around the depending hangar or tubular support 10.

Extending horizontally from opposite sides of the carriage or frame 12 which is enclosed by a spherical or globular shaped casing 19 shown made of two sections 20 and 21 flanged circumferentially as at 22 and joined by a band 23, or otherwise suitably shaped and retained together to permit access to the parts, are a plurality of extended fan supports or arms 24 shown passing through apertures 25 in the casing and coupled to nipples or tubular threaded bosses 26 on the sides of the frame or carriage 12, as by threading or the like so as to render the same removable for facility in assembly, disassembly, shipping or repair. The free ends of these arms are provided with elbows 27 threaded thereon or other suitable angular supports, the depending branches of which carry apertured plugs 28 having pivot ears 29 apertured horizontally to receive pivots 31 disposed through spaced apertured pivot ears 31 formed on motor housings 32 of the fan motors, preferably electric motors which are made streamline or bullet-shaped preferably as shown. The rotors 33 of the motors 32, have their rotor shafts 34 provided with bladed fans 35 preferably all facing in the same direction. These motors are therefore hung from the pivots 30 and as means for supplying current thereto, a disc 36 of insulation or other material is fixed to the hanger 10 above the carriage or frame 12 within the casing 19 to support collector rings 37 and 38 which are embedded in or insulated from the disc 36 and located at the bottom surface thereof in concentric arcs to which line wires 39 and 40 from a source of current supply, lead to the collector or contact rings. The rings are engaged by separate carbon or other brushes 40 and 41 supported in the top of the carriage or frame 12 and resiliently pushed against the same as by means of springs 42. The wires or conductors of the feed lines 39 and 40 are connected to suitable terminals leading to the contact rings or current collector rings

37 and 38. The brushes and springs are supported by nuts or cap screws 43, which form terminals of conductors 44 and 45 both of which lead to the respective motors 32 for supplying current thereto.

As means of controlling the speed of revolution of the plurality of fans about the hanger, the fans are independently driven by their respective motors, under the propulsion force, either suction or pressure caused by the bladed fan wheels in action against the air, a speed governor is provided. For this purpose, a regulator staff 46 disposed vertically in the frame 12 has a needle point bearing 47 in an adjustable bearing screw 48 threaded through an internally threaded bearing sleeve 49 in the top of the frame 12 and adjustable at the top thereof as shown. The staff carries a small pinion or spur gear 50 meshing with the larger pinion or spur gear 16 and adapted to revolve about the same, since the gear 16 is stationary on the hanger 10. The lower portion of the staff has a similar bearing in a correspondingly adjustable bearing screw at the bottom of the frame 12, which parts are numbered the same as those at the top of the staff and frame, thus mounting the staff to turn with the least amount of friction. The lower portion of the staff 46 may be the same size as the upper portion, or may be reduced and in either event, slidably supports a regulator disc or friction brake disc 51 for vertical movement thereon and connected by spring arms 52 with the gear 50 and a sleeve or hub 53 thereof fixed to the staff, or formed integral therewith. The spring arms 52, carry weights or balls 54, which under the centrifugal action by revolving with the pinion or gear 50, move outward and thus raise the regulator and friction brake disc 51 on the staff 46, while normally being lowered when the parts are not turning. A lever 55 is pivoted at 56 to a bearing bracket 57 supported or formed integral with the bottom of the carriage or frame 12 and projecting upwardly therefrom, the inner short arm of the lever having a brake shoe 58 at the bottom to engage the disc 51 but held out of engagement therewith by a spring 59 connecting the outer end of the long arm of the lever to the bottom of the frame or carriage 12 although it may be otherwise suitably positioned or mounted. The bottom of the frame is apertured and provided with an internally threaded sleeve 60 in which an adjusting screw 61 is mounted to engage the underside of the long arm of the lever 55 as more particularly shown in Figure 2 of the drawings and has a knurled operating knob 62 by which it may be adjusted to regulate the distance between the brake shoe 58 and the disc 51. By this means, the speed at which the brake operates within certain limits, may be regulated as desired to control the speed at which the fans revolve about the axis formed by the hanger 10.

Having enumerated the parts, it may be stated that the wiring system is conventional as described, to drive the motors. In operation, when the electric current is switched on or supplied to the collector rings from the line or supply wires, the same will be collected by the brushes and supplied to the motors, so that the latter will be driven to operate the fans, thus setting up an air pressure or suction which will cause the entire assembly to rotate around the stationary support or hanger. The speed regulator or governor, mounted in the carriage together with the small pinion or gear 50, will turn or revolve

about the larger pinion or gear 16 with the whole assembly. The force applied by the fans to the carriage and parts supported thereby will cause the pinion or gear 50 to revolve, exhorting or causing centrifugal force on the governor weights or balls 54 and spring arms 52 to swing them outwardly and causing the regulator or friction disc 51 to rise and engage or contact with the brake shoe 58 of the lever 55, which is held from downward movement by the adjusting screw or stop 61. Adjustment of the distance that the disc 51 can travel, by means of the screw 61, before the disc will engage the brake shoe, by means of the lever 55, will permit regulation of the speed with which the fans and carriage as an assembly rotate around the hanger in a revolving or gyrating movement, in a simple and effective manner.

In view of the foregoing description taken in conjunction with the accompanying drawings it is believed that a clear understanding of the construction, operation and advantages of the device will be quite apparent to those skilled in this art. A more detailed description is accordingly deemed unnecessary.

It is to be understood, however, that even though there is herein shown and described a preferred embodiment of the invention the same is susceptible to certain changes fully comprehended by the spirit of the invention as herein described and the scope of the appended claims.

What I claim is:

1. In a revolving fan speed control, a hanger, a plurality of fans arranged to revolve about the hanger, a governor including a staff mounted to revolve with the fans around the hanger and having drive connection with the hanger, governor means on the staff, a brake disc slidable with the governor according to the speed of rotation thereof and a brake shoe engageable with the disc to control the speed with which the fans revolve about the hanger.

2. In a revolving fan speed control, a hanger, a plurality of fans arranged to revolve about the hanger, a governor including a staff mounted to revolve with the fans around the hanger and having drive connection with the hanger, governor means on the staff, a brake disc slidable with the governor according to the speed of rotation thereof, a brake shoe engageable with the disc to control the speed with which the fans revolve about the hanger, and means for regulating the position of the brake shoe relative to the disc.

3. In a revolving fan speed control, a hanger, a carriage mounted to revolve on the hanger, a plurality of fans carried by the carriage and tending to revolve the same around the hanger, a governor driven in the carriage by said revolution, a brake disc carried by the governor and shiftable according to the speed thereof, a brake lever having a shoe engageable with the disc at a predetermined high speed, and an adjusting means for the lever to determine the speed at which the shoe engages the disc to check the speed thereof.

4. A revolving fan speed control comprising a stationary hanger, a frame mounted thereon to revolve, a gear on the lower end of the hanger, anti-friction bearings between the frame and the gear, a second gear operated by the first gear and rotatably mounted in the frame and having a governor with spring arms and weighted members adapted on the centrifugal action to swing outwardly and inwardly, a brake disc slidably mounted to move with said arms, a plurality of arms on the frame supporting motor fans, a cas-

ing over the frame, a lever pivoted in the frame and having a shoe to engage the disc, means to hold the lever normally disengaged from the disc, an adjusting screw engaging the lever through the frame to adjust the shoe relative to the disc to determine the speed at which the disc engages the brake shoe, and means for driving the fans.

5. A revolving fan speed control comprising a stationary hanger, a frame mounted thereon to revolve, a gear on the lower end of the hanger, anti-friction bearings between the frame and the gear, a second gear engaging the first gear and rotatably mounted in the frame and having a governor with spring arms and weighted members adapted on the centrifugal action to swing outwardly and inwardly, a brake disc slidably mounted to move with said arms, a plurality of arms on the frame, motor fans suspended from the arms, a casing over the frame, a lever pivoted in the frame and having a shoe to engage the disc, means to hold the lever normally disengaged from the disc, an adjusting screw engaging the lever through the frame and casing to adjust the shoe relative to the disc to determine the speed at which the disc engages the brake shoe, and means to supply current to the motors of the fans.

6. In a revolving fan speed control, a hanger, a plurality of arms arranged to revolve about the hanger, fans supported by the arms, a centrifugal governor carried by the arms and driven from the hanger by revolving with the arms, and means controlled by said governor to control the speed with which the arms and fans revolve about the hanger.

7. In a revolving fan speed control, a stationary hanger, a casing rotatably supported on the hanger, a plurality of arms carried by the casing and arranged to revolve about the hanger with the casing, fans suspended from the arms, a centrifugal governor carried by the arms and operatively driven from the hanger as the arms revolve about the hanger, and means controlled by the governor to control the speed with which the arms and fans revolve about the hanger.

8. In a revolving fan speed control, a hanger,

a plurality of fans arranged to revolve about the hanger, a centrifugal governor revolving with the fans about and driven by the hanger, and means cooperative with the governor to control the speed with which the fans revolve about the hanger.

9. A revolving fan speed control comprising a stationary hanger, a frame mounted thereon to revolve, a gear on the lower end of the hanger, anti-friction bearings between the frame and the gear, a second gear engaged with the first gear and rotatably mounted in the frame, governor means rotatable with the second gear within the frame, a plurality of arms on the frame, motor fans suspended from the arms, and means carried by the frame and cooperative with the governor means to regulate the speed with which the arms and fans revolve about the hanger.

10. A revolving fan speed control comprising a stationary hanger, a frame mounted thereon to revolve, a plurality of arms on the frame, motor fans carried by the arms, governor means carried by the frame and operatively driven from the hanger to control the speed with which the arms and fans revolve about the hanger, a stationary disk on the hanger above the frame having contact rings concentrically arranged, brushes carried by the frame and engaging the contact rings, conductors connected to the rings and extending from the brushes to the motors of the fans through the arms and means to supply current to the rings.
